(57) **CLAIM**

The ornamental design for a fishing lure, as shown and described.

DESCRIPTION

FIG. 1 is a front, left, top perspective view of the fishing lure showing my new design;

FIG. 2 is a rear, right bottom perspective view thereof;

FIG. 3 is a front view thereof, the rear view being a mirror image thereof;

FIG. 4 is a top plan view thereof;

FIG. 5 is a bottom plan view thereof;

FIG. 6 is a right view thereof;

FIG. 7 is a left view thereof; and,

FIG. 8 is cross sectional view of the design shown in FIG.4 taken along line 8-8.

The broken lines shown in FIG. 8 depict portions of the fishing lure that form no part of the claimed design.

The present design is a fishing lure called swimbait.

As shown in FIG. 8, the fishing lure has built-in hook and weight.
